(57) **CLAIM**

The ornamental design for a bottle cap, as shown and described.

DESCRIPTION

FIG. 1 is a perspective view of a bottle cap of the present invention, showing the lid of the bottle cap in a closed position.

FIG. 2 is a top plan view of the bottle cap of FIG. 1;

FIG. 3 is a left side cross-sectional view of the bottle cap of FIG. 1, taken along line 3—3 of FIG. 2, the right, opposite, side of which is a mirror image thereof;

FIG. 4 is a front elevational view of the bottle cap of FIG. 1;

FIG. 5 is a rear elevational view of the bottle cap of FIG. 1; FIG. 6 is a left side elevational view of the bottle cap of FIG. 1, the right, opposite, side of which is a mirror image thereof;

FIG. 7 is a bottom plan view of the bottle cap of FIG. 1; FIG. 8 is a perspective view of a bottle cap of the present invention, showing the lid of the bottle cap in an open position.

FIG. 9 is a top plan view of the bottle cap of FIG. 8;

FIG. 10 is a left side cross-sectional view of the bottle cap of FIG. 8, taken along line 10—10 of FIG. 9, the right, opposite, side of which is a mirror image thereof;

FIG. 11 is a left side elevational view of the bottle cap of FIG. 8, the right, opposite, side of which is a mirror image thereof.

FIG. 12 is a front elevational view of a bottle cap of FIG. 8; and,

FIG. 13 is a rear elevational view of the bottle cap of FIG. 8.

The broken lines shown are for illustrative purposes only and form no part of the claimed design.
